UNITED STATES PATENT OFFICE.

NORMAN WIARD, OF WASHINGTON, DISTRICT OF COLUMBIA, ASSIGNOR TO
HENRY R. HUGHES, OF SAME PLACE.

CARPET-STRETCHER.

SPECIFICATION forming part of Letters Patent No. 293,205, dated February 5, 1884.

Application filed November 22, 1883. (No model.)

To all whom it may concern:

Be it known that I, NORMAN WIARD, of Washington, in the District of Columbia, have invented a new and useful Improvement in Combined Carpet-Stretchers, which is made substantially as set forth hereinafter, and as set forth in the drawings accompanying, in which—

Figure 1 shows the entire implement, and Figs. 2, 3, and 4 show details of parts of the same.

The object of this invention is to make a simple combined lever and thrust carpet-stretcher provided with separable parts which can be used at the same time for separate parts of the work of drawing and holding the carpet and driving the tacks therein, as well as serving for extracting tacks and nails.

I make the implement of the two separable parts A B and the attached part C, arranged for use together. The part A forms a lever in the combined implement, as shown in Fig. 1. It has three or other number of sharp points, D, on one end, to engage with the floor or carpet in use, as shown. It has slot E and cross-pivot F therein, arranged to receive and hold the other portion of the implement; and it has a long handle, H, provided with a round flat head, G, on its end, as shown. The points D are turned of steel wire with smooth round points, and are set tightly into drilled holes in the end of lever A. Their shape enables them to penetrate the carpet by passing smoothly between the threads or fibers without injury to them. The part B has a handle arm, K, with a hook, I, on its end, arranged to engage with the pivot F in part A, to combine the two parts for use, and easily separable therefrom when the parts are to be used separately. Its other end is forked into parts

M N. The part M is broad and flat cross-wise, and is curved lengthwise, so as to rest upon the floor and be suited to move freely or rock thereon. Part M has cross-corrugations L on its upper surface, and is curved in relation to the pivot in fork N, so that it will be nearest thereto at the end, as shown by dotted line c. The portion M has a hole and claw-slot, m, arranged for drawing nails, and two claw-notches, m', in its end, as shown, for drawing tacks. The portion N has a pivot, O, by which part C is attached so as to swing

freely, as shown by dotted line c. It has also a hammer-head, P, projecting at its end, as shown, arranged so as to be used for driving tacks. The part C is pivoted to part N, and is formed as shown, and with its end c' broad, to engage with part M, to form a gripping-clutch arranged to receive and hold the edge or fold of the carpet without injury to its fabric while drawing it, and so that it will loosen thereon when the pull is relaxed. The cross-grooves L are arranged with part C to promote this action. The combined parts are arranged for use as in Fig. 1 for drawing and stretching the carpet, using part B C to hold and pull by, and lever A to engage with the floor therefor, the parts being connected by hook I and pivot F or their equivalents.

The part A is used separately as a thrust or push carpet-stretcher, using the points D to engage with the carpet, and the flat head G to push by. By this the wrinkles can be smoothed out of the carpet, and the edge can be drawn into place and held for tacking. At the same time the part B can be used for driving the tacks, as well as for pulling those which may be misdriven.

It will be seen that the implement has peculiar advantages in providing two parts which can be used separately at one time for drawing and holding the carpet and for driving the tacks, while, without additional parts to be provided or looked after, they can be put together and used to draw the carpet into place with great force.

The parts admit of a variety of changes and modifications, some of which are shown in the drawings. In some cases I make the hook on the end of part B to project side-wise, as in Fig. 2, instead of downward, as in Fig. 1, and make for it a hole through part A, as in Fig. 4, instead of the slot and pivot in Fig. 1; or, instead, I make a number of cog-like bearings on the back of lever A, as shown in Fig. 4, to receive and hold this hook, by which the leverage may be changed as it may be required. These and others I use alternatively as equivalents, as preferred.

The cross-corrugations on part M, I make steep on the sides which resist the strain of the carpet, and with inclinations on the other sides substantially that of circles having their

center in the pivot of part C, so that when the carpet is held the arm C will not be made to push down endwise on the carpet by hard pulling, and thus injure the same; nor will it cause the grip to tighten so as not to loosen easily or to endanger breakage.

I prefer to make the parts of soft cast-iron, though they may be made of wrought or malleable metal.

10 I claim—

1. A thrust carpet-stretcher provided with a grip attachment, as described.

2. A thrust carpet-stretcher having bar H, provided with points D, head G, and means 15 for attaching a grip mechanism.

3. The part B, provided with clutch M C and hammer-head P.

4. An implement formed of parts A, B, arranged for use alternatively together and separately in putting down carpets, substantially 20 as and for the purpose set forth.

In testimony whereof I affix my signature in presence of two witnesses.

NORMAN WIARD.
